STEERING WHEEL

Charles W. Beck, Toledo, Ohio, assignor, by
mesne assignments, to Nellie M. Beck, Toledo,
Ohio

Original No. 2,041,738, dated May 26, 1936, Serial
No. 252,251, February 6, 1928. Divided and
this application January 2, 1936, Serial No.
57,230. Application for reissue August 26, 1936,
Serial No. 97,992

4 Claims. (Cl. 74—552)

This invention relates to steering wheels for
motor vehicles, boats and the like and has par-
ticular reference to wheels wherein a solid met-
tallic spider consisting of a hub, spokes and rim
5 is formed of metal and is covered with com-
posite material such, for example, as hard rubber.

This application is a division and continuation
of my co-pending application, Serial No. 252,251,
filed February 6, 1928, and entitled "Steering
10 wheel", patented May 26, 1936, No. 2,041,738.

Heretofore, in the manufacture of wheels
formed of hard rubber, serious difficulty has been
experienced in constructing a wheel having the
necessary strength and durability to resist the
15 shocks and jars incident to operation without
shattering.

The primary object of my invention is to elimi-
nate the difficulty by forming the wheel with a
20 major bulk of composition material such as hard
rubber, in which is embedded an integrally built-
up metallic spider acting therein substantially
as one piece and so associated with the cover-
ing material that these mutually reinforcing com-
ponents together form a unitary, substantially
25 non-shattering structure fully capable of with-
standing the strains and shocks to which a steer-
ing wheel is subjected.

Another object of the invention is to provide
a wheel of the above character distinguished by
30 the simplicity of its construction and the eco-
nomical manner in which the same may be man-
ufactured.

While many prior attempts have been made
35 to obtain a relatively inexpensive and satisfac-
tory steering wheel employing a metallic spider
with a plastic covering thereon, my present in-
vention is believed to represent the first prac-
tical realization of that result through the use
40 of a built-up metallic spider including a hub, an
annular rim reinforcing member and separately-
formed spoke reinforcing members having sub-
stantially integral joints with the hub and rim
members, together with composition material of
45 the nature of hard rubber, embedding the spider
and making therewith a unitary structure which
is substantially non-shattering.

Other objects and advantages of the invention
will become apparent as the description pro-
ceeds, reference being had to the accompanying
50 drawing, in which

Fig. 1 is a fragmentary, plan view of a wheel
embodiment of the present invention; Fig. 2 is a
section on line 2—2 of Fig. 1; and Fig. 3 is a
fragmentary section taken on line 3—3 of Fig. 1.

55 Referring to the drawing, the steering wheel

embodimenting my invention is preferably formed
of a steel frame covered with a suitable plastic,
such as hard rubber, and comprises a hub 1 having
a central tapered bore 2 adapted to receive
5 a steering shaft of a motor vehicle and being
provided with keyways 3 for such purpose. Ra-
diating from the hub 1 are solid metallic spoke
members 4. The spokes are made integral with
the hub 1, in the present instance by being
10 cast therein and for this purpose are provided
with holes 5 through which the metal of the
hub may flow so as to anchor the spokes firmly
in the hub. The spokes may be formed of any
suitable, solid metallic section and in the pres-
15 ent instance are shown as channel shaped, since
the depending flanges of the channels impart
added rigidity to the spokes. It will thus be
seen that the spokes extend into the hub within
the periphery thereof so as to be firmly anchored.

At their outer ends the spokes are connected
20 to a solid annular rim ring 6. The ring 6 is
preferably an endless rod of circular cross-sec-
tion and the spokes are fixed thereto in any
suitable manner, as by crimping the spokes
around the rim or by welding. In any event, it
25 is preferred to so attach the rim 6 to the spokes
as to constitute an integral connection.

In the process of construction, the solid met-
tallic spider which consists of the hub 1, the
20 spokes 4 and the rim 6, is placed in a suitable
mold and the desired covering material such as
rubber is placed into the mold embedding the
spider. The covering material is then vulcan-
ized or otherwise hardened about the spider to
30 form a sheath 8 over the rim, spokes and hub of
the wheel, so disposed that the inner end por-
tions of the spokes 4 definitely extend across the
joint formed by and between the hub 1 and
the sheath or covering 8.

As shown in Fig. 1, the hub 1 is provided with
an annular recess 7 into which the covering ma-
terial is permitted to flow so as to firmly anchor
the same against radial displacement. It will
40 be appreciated that this feature may be omitted
in some instances and the covering secured in
any suitable manner.

It will be seen that a wheel construction in
accordance with the present invention requires
no further operations before being placed di-
rectly on the steering shaft of an automobile or
similar vehicle. Further, the wheel is char-
acterized by the absence of fastening elements for
50 the various metallic parts which are apt to work
loose or shear off in case of an accident. The
wheel may be made exceedingly strong by in-
55

creasing the cross-sectional area of the metallic section used for the spider and the strength is not impaired by the use of screws, rivets or the like.

5. A wheel skeleton or spider built up of separate hub, spoke and rim pieces, in the described or any equivalent manner, employing rim and spoke reinforcing members of solid section and having substantially integral joints which will not loosen 10 through the leverage exerted thereon, especially at the connections between the hub and spoke members, has been found to possess the necessary strength and is cheaper than a spider made in one or two pieces. By embedding such a spider 15 in a plastic composition material whose characteristics are mainly that of hard rubber, which has a fluent phase during vulcanization and becomes intimately bonded to the metal, and employing a spoke and rim section whose bulk or 20 mass is mainly hard rubber, thus avoiding relatively thin or shell-like coverings of the plastic, cracking of the covering is avoided, the metal and plastic mutually reinforce each other, the external contour is defined by the molded plastic 25 rather than the spider, as in wheels made with a poorly adhering, thin cellulosic covering, whose strength and bulk are principally that of the spider, and a substantially non-shattering unitary steering-wheel structure of metal and hard, 30 molded composition material is attained.

While the invention has been disclosed in connection with a particular form and arrangement of the parts, it will be appreciated that various modifications and changes may be made 35 without departing from the invention as defined in the appended claims.

I claim:

1. A steering wheel comprising composition material rim, spoke and hub portions, and a me-

tallic reenforcement for the said wheel, said reenforcement comprising a hub, spokes extending radially of the hub and positively connected thereto, and a rim member connecting the outer ends of the spokes, the hub of the reenforcement 5 being provided with a bore whereby the same may be mounted directly on a steering shaft, the rim and spokes of the reenforcement being embedded within the said composition rim and spoke 10 portions, and the hub of the reenforcement being surrounded by the said composition hub portion, the said connection between the reinforcing spokes and hub being free of the said composition material.

2. A steering wheel as set forth in claim 1 15 wherein the composition spokes and the reenforcement together are of solid formation in cross-section.

3. A steering wheel in accordance with claim 1 20 in which the composition hub portion which surrounds the reinforcing hub is anchored to the latter by the reinforcing spokes so as to prevent relative movement between said composition hub and reenforcing hub.

4. A steering wheel comprising composition 25 rim, spoke and hub portions, and a metallic reenforcement comprising a hub, radial spokes extending into the hub and positively connected thereto, and a rim member connecting the outer 30 ends of the spokes, the hub of the reenforcement being provided with a bore whereby the same may be mounted directly on a steering shaft, the rim and spokes of the reenforcement being embedded within the said composition rim and spoke 35 portions, and the hub of the said reenforcement being surrounded by the said composition hub portion.

CHARLES W. BECK.
